[57] ABSTRACT

A closure for a tank opening with an inwardly directed circumferentially extending catch flange comprising a cover adapted to seat over said opening, said cover having a filling passage and a vent passage therethrough, at least one latch shaft mounted on said

cover for accessibility on the upper side of said cover and extending downwardly to the underside of said cover, said latch shaft being mounted on said cover as aforesaid for movement longitudinally of its longitudinal axis and for movement of rotation about its longitudinal axis, yieldable resilient means urging said latch shaft longitudinally of itself and towards the underside of said cover, a latch extending radially of said latch shaft and having a series of locking flats in echelon arrangement, each locking flat being separated from its neighbouring locking flat by a shoulder, said latch shaft being mounted for rotation as aforesaid adjacent the edge of said cover and said series of locking flats being formed on said latch to cause the locus of the shoulder of each locking flat to cross the downward projection of the marginal portion of said cover in succession starting with the shoulder at the lower most locking flat as the shaft is rotated, a release-turn lever pivotally mounted adjacent the upper end of said latch shaft about an axis transverse to the longitudinal axis of said latch shaft and having a gripping end and a bearing end, a reaction surface on said cover for the bearing end of said lever, said gripping end of said lever being manually depressible to move said latch shaft downwardly against said yieldable means and being turnable to rotate said latch shaft about its longitudinal axis, said cover having a peripheral seal on its underside, said locking flats being adapted in use to engage with the inwardly directed flange of a manhole through manipulation of said release-turn lever.

FIG. 1

MANHOLE COVER LOCK

This invention relates to a closure for a manhole opening in the tank of a tank truck or the like.

Tanks on trucks that carry volatile substances such as gasoline are usually filled through a manhole opening at the top of the tank. In the past, it was common practice to leave the manhole opening open to the atmosphere as the truck was filled. This procedure gave rise to considerable pollution of the atmosphere as vapours were expelled through the manhole as the filling proceeded. In the more recent past, legislation has required collection of vapours from the manhole opening during the filling process and covers for the manhole which provide for the passage of a filler tube, the passage of a tube for vapour transfer return or collection and for a marginal edge seal at the manhole opening have been developed.

Various designs for the marginal edge seal have been devised, but there continues to be a want for a good locking mechanism that can be effectively and quickly mounted in place on the various manhole designs that are encountered in trucks. One of the difficulties with providing an effective seal has been the variation in design of the manhole openings in the tanks. Openings have a downwardly extending catch flange against which the seal lock catches. These flanges vary in depth from truck to truck and there has been difficulty in providing a secure locking mechanism of simple design that is effective for all flange depths.

It is an object of this invention to provide a closure for a tank opening through which one can fill the tank and collect displaced vapours from the tank that has an effective locking mechanism that is easily mounted and demounted on trucks of different manhole designs.

A closure for a tank opening with an inwardly directed circumferentially extending catch flange according to this invention comprises a cover adapted to seat over said opening, said cover having a filling passage and a vent passage therethrough, a latch shaft mounted on said cover for accessibility on the upper side of said cover and extending downwardly of the underside of said cover, said latch shaft being mounted on said cover as aforesaid for movement longitudinally of its longitudinal axis and for movement of rotation about its longitudinal axis, yieldable resilient means urging said latch shaft longitudinally of itself and towards the underside of said cover, a latch extending radially of said latch shaft and having a series of locking flats in echelon arrangement, each locking flat being separated from its next higher locking flat by a shoulder, said locking shaft being mounted for rotation as aforesaid adjacent the edge of said cover and said series of locking flats being formed on said latch to cause the locus of the shoulder of each locking flat to cross the downward projection of the marginal portion of said cover in succession starting with the shoulder of the lower most locking flat, a release-turn lever pivotally mounted adjacent the upper end of said latch shaft about an axis that is transverse to the longitudinal axis of said latch shaft, said lever having a gripping end and a bearing end, a reaction surface on said cover for the bearing end of said lever, said gripping end of said lever being manually depressable to move said latch shaft downwardly against said yieldable resilient means and being turnable to rotate said latch shaft about its longitudinal axis, said cover having a peripheral seal on its

underside, said locking flats being adapted, in use, to engage with the inwardly directed flange of a manhole through manipulation of said release-turn lever.

The invention will be clearly understood after reference to the following detailed specification read in conjunction with the drawings.

In the drawings:

FIG. 1 is an elevation of a closure according to the invention about to be secured into place on a manhole opening of a tank;

FIG. 2 is a plan view of a closure according to the invention;

FIG. 3 is a sectional view illustrating the spring return arrangement and release-turn lever;

FIG. 4 is a perspective illustration of the latch;

FIGS. 5 and 6 are illustrations showing the latch revolved to a lock position; and

FIGS. 7 and 8 are illustrations similar to FIGS. 5 and 6, but showing the device locked at a different locking flat with a manhole flange of lesser dimension.

The numeral 10 refers to a closure for a manhole opening in the tank of a tank truck or the like which is designed to carry a volatile substance such as gasoline. It has a top surface best seen in FIG. 2 and a downwardly extending flange 12 that is inserted into the manhole opening 14 of the tank of a tank truck. The tank has not been fully illustrated because of its well known nature. The manhole opening 14, however, has a downwardly extending flange 16 and in use, it is customary to provide a locking means that has a latch that engages with the lower edge of the flange 16 to pull the closure 10 downwardly against the opening and maintain the peripheral seal 18 thereof in tight engagement with the upper edge of the flange 16. Filling of the tank 30 takes place through fill tube 11 and venting of vapours takes place through vent tube 13 in accordance with standard practice.

As indicated in the preamble to this invention, the flange 16 varies in depth from tank truck to tank truck 40 and there has been difficulty in providing a suitable latch design that will maintain a tight seal for all manhole flange designs. This invention fulfills that need in that it provides a simple and reliable device capable of making a secure closure seal for various manhole designs that can be applied with a minimum of effort.

The flange 12 is cut away at the location of two similar latch assemblies that are manipulated from an inoperative position as illustrated in FIG. 2 to an operative position where they engage with the underside of the flange 16 as will be described.

The latches 20 of the similar latch assemblies are each rigidly mounted on the free end of a latch shaft 22 and secured thereto by means of a nut 24. Latches 20 have a rectangular hole to receive the keyed free end portion of the shafts 22.

The latch shaft 22 in each case is mounted on the cover 10 within a sleeve 26 that is welded to the cover and a compressed coil spring 28 bears against a shoulder 30 at the lower end of the sleeve 26 and a shoulder 60 on the shaft 22 as at 32 to normally urge the shaft in an upward direction.

Shaft 22 has a head 34 secured to its upper end by means of a pin 16. Numeral 38 is a seal to seal the shaft to its housing against the escape of vapours of the tank in use. The upper end of the head 34 is bifurcated and a release-turn lever 40 is pivotally mounted therein by means of a pin 42. The short end of the lever 40 carries

a reaction wheel 44 that is adapted to rotate with respect to the shaft and that bears against the reaction surface 46 of the sleeve 26.

It will be apparent that by manually depressing the free end of the lever 40 in the direction of the arrow 48, 5 the latch shaft will be depressed downwardly within the sleeve 26 against the pressure of the spring 28.

It will also be apparent that by rotating the lever about the axis of the latch shaft 22 the latch shaft can be rotated. In this respect, it will be recalled that 10 44 is a wheel and rotates with respect to the lever to permit easy movement of the latch over the bearing surface 46.

The release operation of the lever 40 whereby the latch shaft can be depressed in the direction of the 15 arrow 50 by downward movement of the free end of the lever in the direction 48 is illustrated in FIG. 3. The turn action of the levers 40 whereby the latches 20 can be rotated from an inoperative position illustrated in FIG. 2 to an operative position where they underlie the 20 edge of the flange 16 of a manhole opening is indicated by the arrows 52 in FIG. 2 of the drawings.

The design of the latch member 20 at its free end is illustrated in FIG. 4. It consists of a series of locking flats 56 arranged from the bottom in echelon arrangement and separated one from the other by shoulders 58. As the levers 40 are rotated in the direction of arrows 52, the locus of the shoulders 58 crosses the downward projection of the marginal portion of the cover 10 in succession starting with the lowermost shoulder so that the flats 56 will underlie in succession the lower marginal edge of the flange 16 of the manhole opening until a shoulder 58 engages the side of the flange 16. One of the shoulders 58 will engage the lower marginal portion of the flange 16 depending 30 upon the relative height of the flange and latch member 20.

In FIG. 3, for example, it will be apparent that if one were to merely rotate the lever 40 in the direction of arrows 52 the second shoulder from the bottom would engage with the flange 16 and the first locking flat would underlie the flange 16. There would, however, be no locking force on the seal. In order to achieve a locking force, one would depress the handles 40 in the direction of arrow 48 to move the latch shaft downwardly of the position illustrated in FIG. 3 and then rotate them in the direction of arrows 52. By this manner of operation, a shoulder higher than the first one would engage with the flange 16 to arrest rotation in directions 50 52 and when the levers 40 are released, spring 28 would force the shaft 22 in an upward direction to 45 spring urge latch flats against the bottom edge of the flange 16.

FIG. 5 is an illustration of the device locked to the manhole flange 16 on the second locking flats from the bottom. In this case, the release-turn levers 40 have been depressed in direction 48 to bring the second locking flat below the level of the flange 16 and then rotated in direction 52 to bring the respective locking shoulders in contact with the marginal portion of the flange 16 and then released to permit the springs 28 to lock the locking flats against the lower marginal edge of the flange.

FIGS. 7 and 8 show a flange 16 on a manhole cover that is of a lesser depth in which case the lever 40 is rotated further to achieve a locking function with a higher locking flat.

In use, the closure described is an integral part of the loading head which includes the fill pipe 11 and the vapour collection pipe 13 and the entire assembly is carried by the free end of the loading arm. The tank trucks pull up to the loading bay and the assembly head as described is swung into position above the open manhole in the top of the tank truck compartment. The loading arm is lowered until the head is onto the manhole collar and it is then clamped into position by depressing and rotating the levers 40 as described. The fill pipe 11 has a ball joint generally indicated by the numeral 60 for flexibility. The joint is indicated in a solid line and a dotted line position. It can assume either of these and many other positions to assist in proper alignment.

It will be apparent that the release-turn levers which are first operated in a downward position to release or depress the latch against the pressure of the holding spring and then rotated to achieve interlock with the flange provide an easy to operate and a positive latch for manholes having various depth flanges.

Embodiments of the invention other than the one described will be apparent to those skilled in the art.

What I claim as my invention is:

1. A closure for a tank opening with an inwardly directed circumferentially extending catch flange comprising

a cover adapted to seat over said opening, said cover having a filling passage and a vent passage therethrough,

at least one latch shaft mounted on said cover for accessibility on the upper side of said cover and extending downwardly to the underside of said cover, said latch shaft being mounted on said cover as aforesaid for movement longitudinally of its longitudinal axis and for movement of rotation about its longitudinal axis,

yieldable resilient means urging said latch shaft longitudinally of itself and towards the underside of said cover,

a latch extending radially of said latch shaft and having a series of locking flats in echelon arrangement, each locking flat being separated from its neighbouring locking flat by a shoulder,

said latch shaft being mounted for rotation as aforesaid adjacent the edge of said cover and said series of locking flats being formed on said latch to cause the locus of the shoulder of each locking flat to cross the downward projection of the marginal portion of said cover in succession starting with the shoulder at the lower most locking flat as the shaft is rotated,

a release-turn lever pivotally mounted adjacent the upper end of said latch shaft about an axis transverse to the longitudinal axis of said latch shaft and having a gripping end and a bearing end,

a reaction surface on said cover for the bearing end of said lever,

said gripping end of said lever being manually depressible to move said latch shaft downwardly against said yieldable means and being turnable to rotate said latch shaft about its longitudinal axis, said cover having a peripheral seal on its underside, said locking flats being adapted in use to engage with the inwardly directed flange of a manhole through manipulation of said release-turn lever.

2. A closure for an opening with an inwardly directed circumferentially extending catch flange as claimed in claim 1 having two latch shafts,

said latch shafts being mounted for rotation as aforesaid in opposite directions by their respective release-turn levers.
